UNITED STATES PATENT OFFICE.

FRED S. ENGLISH, OF NEW LONDON, CONNECTICUT.

EXTENDED DELIVERY FOR PRINTING PRESSES.

Application filed April 10, 1920, Serial No. 372,822. Renewed June 20, 1924.

To all whom it may concern:

Be it known that I, FRED S. ENGLISH, a citizen of the United States, and a resident of the city and county of New London, State of Connecticut, have invented certain new and useful Improvements in Extended Deliveries for Printing Presses, of which the following is a specification.

My invention relates to a device for delivering the printed sheets from a printing press or other machine onto a table or support arranged beyond or extended from the printing press proper.

In the ordinary printing presses the sheets are delivered upon a table arranged over a part of the printing press mechanism and the pile table is generally stationary so that the first sheet delivered falls from the delivery device upon the table and succeeding sheets pile upon the previously delivered sheets, each succeeding sheet falling a lesser distance; and when the pile becomes too high for the delivery device to properly deposit the sheets it is customary to remove the pile from the pile table by hand to make room for succeeding sheets.

Where the table is arranged over part of the press the number of sheets which can be piled upon it is very limited and if the sheets are at all thick it is necessary to remove the piles from the table often. The present device relates to that class of apparatus wherein the sheets are delivered beyond the ordinary limits of the printing press onto a pile table which is movable and upon which a large number of sheets may be piled.

One of the objects of my invention is to provide an extended delivery device which may be very easily and very quickly attached to an ordinary printing press. The present device requires no modification in the construction of the press proper, so that it may be readily applied to presses now in use. Another object of my invention is to provide an extended delivery device in which perfect alignment with the press is not absolutely necessary. Another object is to provide an extended delivery apparatus which may be applied to the press in such manner that the ordinary delivery device of the press may be used as part of the extended delivery device. This makes the extended delivery device economical and facilitates its adaptation to the presses.

Other advantages will be pointed out in the detailed description hereinafter.

In the drawings forming part of this application,

Figure 1 is a side elevation of part of a two revolution printing press having my invention applied thereto,

Figure 2 is a sectional view taken on the line 2—2 of Figure 3, and showing parts of the delivery device in front elevation.

Figure 3 is a plan view of the extended delivery device and of the lowering device.

I have shown the side frame 115 of a two revolution, flat bed printing press and the impression cylinder 116. The delivery device is adapted to take the sheets singly as they come from this impression cylinder and to deliver them upon the pile table arranged beyond or in front of the press. At

1 I have shown the ordinary carriage of a printed side up delivery device and this carriage has wheels 2 at the rear end and similar wheels 3 at the forward end which run on tracks 4 at each side of the press. At

the forward end of the carriage there is a tape roller 5 turning freely on a rod and over this roller the tapes 18 engage. These tapes correspond with the tapes in the patent to Fenner No. 719,317 and they perform the same function; that is, they receive the sheets as they come off the impression cylinder and carry them, printed side up, to a point at the end of the press proper or over the inking device.

In former practice these tapes peeled or turned away under the sheet upon the rearward motion of the carriage and let the sheet fall upon a pile table arranged over the inking device. But in the present case these tapes deliver the sheet upon another set of tapes which carry the sheets to the extended pile table, as will appear. Above the tapes 18 there are other tapes 6, which are endless and travel over the rear rollers

6^b and over forward rollers 6^a, the tapes 6 being inclined, so that their lower runs converge toward the tapes 18 and impinge upon the roller 5 at the forward end of the carriage. The sheets carried by the tapes 18 are engaged on their top surface by the tapes 6 (which are generally in the form of round belts) and the latter cooperate to prevent the sheets from flying off the tape belts 18 and assist in carrying the sheets forward.

The tracks 4 usually extend only to the

forward end of the press proper and in the present structure I have arranged supplemental or extension tracks and I have provided an extension on the delivery carriage 5 which travels on these extended tracks.

The carriage extension consists of bars 7 which are secured at one end to the bars 1 by means of the plates 20. The connection between the bars 7 and 1 is a pivotal 10 one so that the forward part or extension of the carriage may pivot vertically in relation to the rearward part in order that the device may operate smoothly regardless of whether the track extensions are parallel 15 with the tracks 4. On the bars 7 there is mounted an idle roller 8 which corresponds with the roller 5. Certain of the endless tapes on the carriage marked 18, engage 20 around the roller 5 for the purpose of carrying the sheets up to this roller, whereas other endless tapes 19, which lie parallel with the tapes 18, and preferably alternate side by side with the latter, pass around the roller 8, with their upper and lower runs 25 straddling the roller 5. Except for their engagement with the roller 8 instead of the roller 5 these tapes are connected with the same parts and are operated the same as the tapes 18. As the tapes 18 and their operation 30 are well known in the art and are described in said Fenner patent, a more complete description thereof is unnecessary here.

The extension bars 7 also carry rollers 9^b corresponding with the rollers 6^b, and there are forward rollers 9^a corresponding with the roller 6^a. Endless belts 9 engage over these rollers 9^a, 9^b and they converge toward the tapes 19. These belts serve to keep the sheets from flying off the tape belts 19 and assist in carrying the sheet forward. The rollers 9^b on which the belts 9 engage are mounted upon the shaft 12 and the latter is operated from the roller 8 by means of a crossed belt 15 engaging over the pulleys 14 and 13 arranged respectively on the shaft 40 12 and roller 8.

The rollers 10 travel on the track rails 11. These latter are bolted at one end to the pile table frame at one point by the bolts 21 and at the opposite end they are bolted to the forward ends of the track rails 4 by bolts 22. The track rails 11 may be in the same plane as the rails 4 or they may incline upwardly or downwardly therefrom, the connections permitting of this. The tracks 11 do not have to be aligned with the tracks 4 and the attachment of the extended delivery to the press is made very easily. As the forward extension of the delivery carriage, i.e. the bars 7, are pivotally connected to the bars 1, the part of the carriage which travels on the tracks 11 will operate even if the latter are not aligned horizontally with the tracks 4.

As the sheet comes out from the impres-

sion cylinder 116 the carriage is moving forwardly or away from the cylinder, starting at about the time the head of the sheet leaves the cylinder; and when the carriage gets to the end of its forward stroke the sheet will 70 have been carried forward so that its rear end lies a short distance ahead of the cylinder and the sheet will lie on the tapes 18. When the carriage moves back again toward the cylinder the sheet remains stationary 75 during this movement of the carriage and the sheet will be in the bight of the tapes 6 and the roller 5.

As the carriage starts forward on its second cycle another sheet starts out from the cylinder upon the carriage tapes 18; and the first sheet is carried forward with the carriage, being held at its leading edge in the bight of the tapes 6 and the roller 5 until the carriage reaches the end of its forward stroke when the first sheet will be about over the ink fountain. As the carriage moves back again toward the cylinder the tapes 6 and roller 5 move back in relation to the sheet, leaving the latter in its advanced position. When the carriage is back near the cylinder it will have completed two cycles and there will then be a sheet resting on the tapes 18 not far ahead of the cylinder and a sheet ahead of it, resting on the tapes 19 95 with its leading edge in the bight of the tapes 9 and roller 8.

The carriage will now start forward on its third stroke and the first sheet will be carried out over the pile table by the tapes 19. 100 As the carriage starts backward again the tapes 9 and roller 8 run back over the sheet and this sheet falls on the pile table. The same action takes place with each successive sheet.

The pile table may be very simple in construction. I have shown a pair of forward legs or supports consisting of bottom plates or feet 23 adapted to be bolted to the floor or foundation on which the press is mounted; of the uprights 24, and the castings 25 mounted on the tops thereof.

The rear legs consist of the base castings 26 which rest on the floor or foundation near the press, of the upright posts 27, and the top castings 28. The legs are connected back and front by the side channel irons 29 and 30 and they are tied crosswise by the tie rods 113 and 114. The pile table 31 on which the sheets are piled, is supported upon T irons 32, extending across and underneath the table and these T irons have hooked ends which engage the ordinary shackles 33. There is a pair of these shackles at each side of the pile table and they are carried upon the lower ends of the cables 31* which extend upwardly to the top of the pile table and pass partly over the forward and rearward sheaves 34, 35, at opposite sides of the table frame. From the sheaves 34, 35, the 125 130

cables pass over the sheaves 36, to the winding drums 37, fixed to the opposite ends of a shaft 38.

The table 31 starts to receive sheets from the delivery carriage when the table is in its raised position and the table is lowered gradually or step by step with the cables 31^a until the required amount of sheets have been piled upon it or until the table has reached its lowermost position, and a truck may be run under the table, receive the descending table and pile upon it, whereupon the shackles 33 can be unhooked from the T irons 32. The entire table and pile may be moved away upon the truck and there is room for the truck to be removed at the sides or the front of the table frame. The T irons 32 may be replaced in the shackles, another table placed thereon, and the table raised to the uppermost position to receive another pile. The pile table, it will be noted, is placed to the front of and beyond the press and it has a vertical movement from approximately the height of the delivery carriage nearly to the floor so that it is adapted to receive a much larger pile than if the table were on some part of the press.

The operation of the device has been set forth in the above description. As the carriage reciprocates periodically and in time with the operation of the press the sheets are received singly upon the carriage tapes and they are advanced in three successive stages upon the carriage until they reach their final position on the tapes above the piling table. When a sheet reaches this position it is deposited at the next rearward movement of the carriage upon the pile table or upon the topmost sheets of the pile. No additional mechanism is required other than the extension of the carriage and the additional tapes, in order to carry the sheets beyond the press to the extended pile table, so that the device is very simple. As the extended portion of the carriage travels over the extension rails and since the carriage extension can articulate, it is not necessary that the extension part of the delivery align perfectly with the remainder of the delivery. As the sheets are deposited upon the top of the pile they are jogged from all four sides to make the pile even.

Having described my invention, what I claim is:

1. The combination with a printing press and a delivery table arranged beyond the press, a delivery carriage on the press adapted to convey the printed sheets from the impression cylinder, and an extension on said delivery carriage adapted to receive the sheets from the delivery carriage said extension being adapted to reciprocate and to move to a position over said delivery table.

2. The combination with a printing press and a delivery table arranged beyond the

press, a delivery carriage on the press adapted to convey the printed sheets from the impression cylinder, and an extension pivotally connected to said delivery carriage, and adapted to receive the sheets from the delivery carriage, said extension being adapted to reciprocate with said carriage and to move to a position over said delivery table.

3. The combination with a printing press and a delivery table arranged beyond the press, tracks over the printing press, a reciprocating carriage movable on said tracks and adapted to carry the printed sheets from the impression cylinder of the press, extension tracks extending from the press over said delivery table, an extension pivotally connected with said carriage and arranged to travel on said extension tracks, and means for advancing the sheets on the carriage and extension.

4. The combination with a printing press and a delivery table arranged beyond the press, tracks, a carriage reciprocating on said tracks over the press, an extension on said carriage reciprocating over said delivery table, belts on said carriage for advancing sheets on the carriage, belts on the carriage extension adapted to receive the sheets from said first mentioned belts and adapted to carry the sheets over said delivery table.

5. The combination with a printing press and a delivery table arranged beyond the press, a delivery carriage reciprocating over the press, an extension on said delivery carriage reciprocating over said delivery table, and means for advancing sheets by successive steps over said carriage and said carriage extension.

6. The combination with a printing press and a delivery table arranged beyond the press, a delivery carriage reciprocating over the press, an extension on said delivery carriage reciprocating over said delivery table, and means for advancing sheets by successive steps over said carriage and carriage extension and comprising belts arranged to receive the sheets one from the other in substantially the same plane.

7. The combination with a printing press and a delivery table arranged beyond the press, a delivery carriage reciprocating over the press, an extension on said delivery carriage reciprocating over said delivery table, and means for advancing sheets by successive steps over said carriage and carriage extension and comprising belts adapted to convey the sheets to the forward end of the carriage, other belts extending in substantially the same plane as said first belts and extending beyond the same to the forward portion of the carriage extension and adapted to receive the sheets from said first mentioned belts.

8. The combination with a printing press and a delivery table arranged beyond the

press, a delivery carriage reciprocating over the press, an extension pivotally connected with the carriage and reciprocating over said delivery table, and means for advancing sheets over said carriage and extension and comprising a roller arranged at or adjacent to the pivotal connection of said carriage and extension, belts passing around said roller for carrying the sheets over the carriage, a roller near the forward end of said

extension and other belts, passing over said last mentioned roller and adapted to receive the sheets from said first mentioned belts and adapted to carry them over said extension to be deposited on said delivery table. 15

Signed at New London, in the county of New London, and State of Connecticut, this 29th day of October, 1919.

FRED S. ENGLISH.
